DESIGN FOR A JEWELRY STONE

George A. Armstrong, Cranston, R. I., assignor to William C. Greene Company, a corporation of Rhode Island

Application July 25, 1936, Serial No. 64,048

Term of patent 7 years

To all whom it may concern:

Be it known that I, George A. Armstrong, a citizen of the United States, residing at Cranston, in the county of Providence and State of Rhode Island, have invented a new, original, and ornamental Design for a Jewelry Stone, of which the following is a specification:

In the accompanying drawing which forms a part of this specification,

Figures 1, 2, and 3 are a front view, a side view and a lower end view respectively of a jewelry stone embodying my invention, and

The characteristic feature of my design resides in the substantially triangular portion shown in the lower left hand corner of the stone, the triangle being ornamented by jewels and beaded borders as shown.

I claim:—

The ornamental design for a jewelry stone, as shown and described.

GEORGE A. ARMSTRONG.
